LOCK HINGE.

No. 394,605.

Patented Dec. 18, 1888.

UNITED STATES PATENT OFFICE.

WILLIAM P. PATTON, OF HARRISBURG, PENNSYLVANIA, ASSIGNOR OF
ONE-HALF TO EDWIN I. NOTTINGHAM, OF WASHINGTON, DISTRICT
OF COLUMBIA.

LOCK-HINGE.

SPECIFICATION forming part of Letters Patent No. 394,605, dated December 18, 1888.

Application filed April 2, 1888. Serial No. 269,401. (Model.)

To all whom it may concern:

Be it known that I, WILLIAM P. PATTON, a legal resident of Harrisburg, Dauphin county, Pennsylvania, and a citizen of the United States, residing temporarily at Washington, in the District of Columbia, have invented certain new and useful Improvements in Lock-Hinges for Window Shutters, Blinds, or Gates; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to an improvement in lock-hinges that are adapted to secure window shutters, blinds, or gates in desired position.

The object of my present invention is to produce a hinge of the type mentioned which will lock a window shutter or blind in an open or partially-open position, the hinge being right or left handed, as desired.

A further object is to provide a lock-hinge which may be produced complete without employing cores in the molding operation, it being understood that the hinge is to be cast into form, using metal as a material.

A further object is to afford a light, strong, and neat lock-hinge which may be produced in quantity by ordinary methods of manufacture at a low initial cost.

With these objects in view my invention consists in certain features of construction and combinations of parts, which will be hereinafter described, and pointed out in the claims.

Referring to the drawings making a part of this specification, Figure 1 is a side elevation in perspective of the lock-hinge in an open locked position. Fig. 2 represents the hinge in elevation, showing the working or joint portion in section. Fig. 3 is a side elevation of the complete hinge opened and with its locking parts released from connection, ready to swing and close the shutter or blind. Fig. 4 shows the hinge completely closed with

both leaves in contact. Fig. 5 is a top plan view of the hinge with the leaves extended to lie in the same plane. Fig. 6 is a plan view in section of the lock-hinge, taken on the line *x*, Fig. 3, showing the position assumed by the sliding pintle when the locking parts are separated and the movable leaf released to swing and close the shutter to which it is secured. Fig. 7 is a view in perspective of the fixed leaf of the hinge with the upper portion broken away. Fig. 8 is a bottom plan view of the fixed leaf or the half-section of the hinge which is secured to a window-casement. Fig. 9 is a plan view in section of a hinge in position on a shutter and window-casement, also indicating by an operator's hand the method of applying pressure to release the lock of the hinge and allow its loose leaf to rotate. Fig. 10 is a front elevation in perspective of the hinge. Figs. 11 and 12 show plan views of the hinge in cross-section, exhibiting the working parts adjusted to lock at an angle of forty-five degrees and ninety degrees, respectively. Figs. 13, 14, and 15 are views of parts of the hinge detached. Fig. 16 is a sectional elevation of a fixed leaf and an attached locking-plate, showing a modified means for securing the parts together. Figs. 17 and 18 show other modifications of the hinge.

Two hinges are employed on each shutter to swingly support it, and as these are preferably made duplicates of each other it will only be necessary to give a detailed description of a single hinge.

A A' are hinge-leaves provided with the usual countersunk holes for the reception of wood-screws to fasten them in place. The portion of the hinge of which A is the retaining-leaf is intended to be secured to the window frame or casement. It is extended laterally to produce a bracket-plate, A², which is of such a relative length as to afford a proper base for a locking-plate, which will be more specifically described. The bracket-plate A² has an integral flange or table, *a*, formed on its top edge, this table lying in a horizontal plane when the hinge is in position for service.

It will be seen on inspection of Fig. 8 that

the bracket-plate A² is offset at *m*, so as to throw its outer portion out of direct line with the leaf-piece A, but in a parallel plane to the latter.

5 Upon the under side of the table *a*, integral with it and the bracket-plate A², a boss, *a'*, is formed, which is perforated, together with the plate *a*, to afford a screw-hole, *s*. (See Fig. 7.)

The inner edge of the leaf A is integrally projected a short distance toward the hole *s* in the table *a*, forming a rib that projects above the upper surface of this table, the terminal end of the rib being preferably cut V-shaped, as shown in Fig. 7, to form a locking-toe, *e*, the use of which will be shortly explained.

Upon each side of the leaf A the table *a* is extended to form stiffening flanges or ribs *f*, *f'*, so as to render the connected leaf and bracket-plate strong at their point of junction and avoid the use of a bulk of metal to attain such necessary rigidity and cohesive strength. The upper surface of the table *a* is level, and it is preferably rounded or ovate in form of its peripheral edge. Upon it is mounted the locking-disk B, which is shown detached from other parts in Figs. 13 and 15. As will be seen in these figures, the locking-disk B consists of a circular disk of metal, with a conical or spherical protuberance, B', formed on its upper face, and from the center of this conical inclined plane a cylindrical pintle, D, projects vertically. The circular border-line *n*, which terminates the conical base B' of pintle D, is of such a relative diameter to that of the locking-disk on which it is formed that a flat circular track or rim, *o*, is produced between these curved border-lines.

At a point, *r*, on the top surface of the track *o* a gradual upward inclination is produced by a thickening of the material to afford a laterally-curved inclined plane, B², that terminates in a shoulder, *d*, which is formed by an open slot or notch, *h*, that is cut in the peripheral edge of the locking-plate B at this point. The width of the slot *h* is determined by the distance between the shoulder *d* and an opposite shoulder, *d'*, that is the terminal edge of a similar inclined plane, B³, which is located on the track *o*. This shoulder *d'* is preferably made slightly higher than the shoulder or terminal edge of the inclined plane B².

It will be noticed that the inclined surface of the conical base B' is extended downwardly between the shoulders *d* *d'* to the point *u* at the lower edge of the plate B, (see Fig. 13,) so that a continuous inclined surface is afforded at this point from the lower end proper of the pintle D to the point *u*. The edge of the locking-disk B is indented with notches of a proper size and shape to register with the locking-toe *e*, that is formed on the leaf A, as has been explained. There may be any desired number of these notches; but in practice three are about all that will be necessary—shown at 1 2 3 in the figures, the notches 1

and 3 bounding one-fourth of the circumference of the circular locking-disk B. The locking-disk B is preferably secured in place 70 by a set-screw, *b*, which is inserted through the perforation *s* in the table *a* and boss *a'* into a central tapped hole in the body of the locking-disk B, as shown in Fig. 2; but other plans of connecting the parts may be used. 75

The leaf A' is the one that is secured to the edge of the shutter near its lower end, which in the hinge I have elected to describe, for convenience, I prefer to so locate. It is projected from the portion which is affixed to the 80 shutter, so that a shallow box or recessed plate, C², may be afforded which is given the form substantially as shown in Figs. 2, 4, and 6. As will be seen, the edges of the recessed cavity in the leaf-extension C² are vertical 85 and parallel, and are sloped from the outer edge of the face *k*, which is in the same plane with the surface of the leaf A'.

The width from the edge *t* to the edge *t'* (see Fig. 2) of the recess just mentioned is 90 preferably made equal to twice the diameter of the pintle D, and the height of the same is somewhat greater than the length of the pintle from the crown of the conical base B' to its upper extremity, to allow the recessed leaf 95 to be moved toward the other leaf when the two are connected by the pintle D. The depth of the recess in the leaf-extension C² is slightly in excess of the half-diameter of the pintle D, and a cap-plate, C, (shown detached in 100 Fig. 14,) which is recessed to exactly mate with the cavity made in the leaf-extension C², is placed to cover it, the said plate having ears *c*, which are perforated to align with similar holes in the leaf-extension C², so that the 105 two pieces may be secured together by rivets, and thus provide a socket having a transverse diameter that will loosely fit the pintle D, while the width from *t* to *t'* of this cavity C² is sufficient to allow the pintle to slide from 110 one of these edges, *t*, to the opposite one, *t'*. (See Fig. 6.)

On the lower edge of the cap-plate C (see Fig. 14) a depending lug, C', is integrally formed, which is intended to fit into and interlock with the notch or open slot *h* in the edge of the locking-disk B when the shutter is opened or partially opened, as the situation may require. The length, considered vertically, of the locking-lug C' is such in proportion to the height of the inclined plane B² that when the lug is in the position shown in Fig. 4, where it rests upon the track-surface of the locking-disk B, the leaf A' and its attachments will be supported at a proper height to 120 afford a clearance distance between the outer lower edge, *d*², of the socket-box C² and the upper edges of the shoulders *d* *d'*, and in consequence the swinging leaf A' may be readily revolved on the foot of the lug C', and also on the lower edge of the socket-box C², which will then have a contact with the inclined surface on the crown of the conical base B'. The lower inner edge of the socket-box C² is 125 130

rounded off to afford a free entrance to the pintle D, and also provide a broader surface for contact of this socket-box with the crown of the conical base B'.

5 In operation, if the shutter to which the hinge is attached is placed in a situation which will allow it to swing and nearly touch the vertical wall of the building, as shown in Fig. 9, the locking-disk B is placed so that its notch 10 or serration 1 is so located, relatively, that the locking-lug C' will engage the notch h in the locking-disk B when the two leaves A A' are in the same or parallel planes nearly coincident. When the parts are adjusted as stated, 15 the shutter, if closed and thrown open by pressure of the hand of an operator against its inner surface, will by its momentum cause the locking-lug C' to move up the inclined plane B', and when it is in a position above 20 the notch h the lug will drop into the notch with which it is adapted to mate, and thus lock the shutter in an open position close to but not touching the wall of the building.

It should be explained that the notch h is 25 tapered slightly, the side walls or shoulders, d d', rendering it wider at the top than at the bottom, which will facilitate the withdrawal of the locking-lug C' when it is desired.

When the shutter is to be closed, the hand 30 is applied to the outer surface of the shutter near the lower hinge, as shown in Fig. 9, in which O represents the shutter in open position, P the wall of a building, G the window-casing, and R the hinge in section. If 35 the fingers of the operator are now pressed with moderate force inwardly, the leaf A' and the attached shutter will be caused to move upwardly and inwardly by reason of an engagement of the lower end of locking-lug C' 40 with the inclined surfaces of the conical base B' at this point. As has been previously shown, the sloping surfaces of this conical base extend downwardly between the shoulders d d', so as to permit the engagement of 45 the locking-lug C' in the manner just mentioned. When the shutter is pressed to slide as just stated, the pintle D will resume the position shown in Fig. 9, and by a simultaneous inwardly-swinging movement in the 50 direction of the arrow the shutter will be readily closed.

As all the weight of the shutter is made to bear on the lower edge of the socket-box C² and the locking-lug C', this lug will be held 55 in close contact with the conical base B' at its lower portion, and thus draw the socket-box on the side opposite the lug C' against the pintle, so that a smoothly-working joint without rattle is thus afforded, the joint being 60 held from lateral motion throughout its entire swinging movement when a shutter is opened or closed.

Should it occur that the shutter cannot swing entirely open by reason of obstructions— 65 such as walls or fences—preventing the same, a lock may be effected at an angle of forty-five degrees, or at a right angle with the wall

P, instead of parallel to it, as has been explained, by first relaxing the screw b, which is used to secure the locking-disk B upon the 70 table a, and shifting the disk to bring the V-shaped notch 2 into line with toe e, and then clamping the pieces together by the screw b, if an angle of forty-five degrees is desired, or into the notch 3, if a right angle or ninety degrees removal of the shutter from the wall P is necessary.

It is obvious that other notches may be 75 cut in the edge of the disk B to afford means for changing the locking-point of the hinge to 80 a different angle than those shown; hence I do not wish to limit myself to three notches.

In Fig. 16 a modified form for a revolute engagement of the locking-disk B with the table a or bracket-plate A² is shown. This 85 consists in the provision of an integral depending pintle, p, which is inserted through a neatly-fitting hole formed in the table a and boss a', this pintle taking the place of a setscrew, b, and may be employed in some hinges 90 where a sufficient weight of shutter is imposed upon the locking-disk to retain it in place, it being understood that the notches 1 2 3 and locking-toe e are utilized, as has been previously explained.

The locking-notches 1 2 3 may be dispensed with and spaced perforations made in the table a, which are adapted to receive a depending pin formed on the under side of the locking-disk, thus affording a similar lock in 100 substantially the same manner as is effected by the V-shaped notches 1 2 3 and locking-toe e.

In Figs. 17 and 18 are shown views of another slightly-modified form of the hinge, 105 whereby it is adapted for use as a right and left hand hinge at will. Fig. 17 is a side elevation of the leaf which is affixed to the window-casing, the working parts attached thereto being in section taken through the 110 axial center of the pintle, the remaining figure (18) representing a front elevation in section of the parts taken on the line y y, Fig. 17. The boss a' of the bracket-plate A² is widened laterally, as shown in Fig. 18, and is located at 115 its center of width on the bracket-plate A². This construction of parts will allow the depending small pintle p, which is formed on the lower side of the locking-disk B, to engage either one of the parallel vertical perforations p', made in the boss a', and thus locate the upper pintle, D, to the right or left of a center line, to afford folding action on either 120 side of the leaf A, and thus produce a right or left hand hinge.

If the hinge is made to fold in either direction, so as to suit right or left hand shutters, it will be necessary to countersink the screw-holes in the leaves on both sides, as is shown, the material being thickened up around the 130 holes on each side of the leaves to admit this without making the whole leaf heavy enough to allow countersinks to be so formed.

By a reversal of the locking-disk B with re-

gard to the swinging leaf A', and changing the position correspondingly of the locking-toe e, the hinge may be thus adapted to lock a gate in closed adjustment, the opening of which may be effected by an edgewise pressure applied to the gate in an obvious manner.

It is feasible to produce the socket-box and the leaf A' integral with each other by use of a core; but I prefer to form the socket-box employing the cap-plate C, as this method of construction allows the hinge to be made without the use of a core by snap-flask molding, such as is commonly employed in the manufacture of light hardware in small pieces.

Other minor changes may be made in the details of construction of the hinge without exceeding the scope of my invention; hence I do not desire to restrict myself to the exact forms herein shown; but,

Having fully described my invention, what I claim as new, and desire to secure by Letters Patent, is—

1. The combination, with a hinge-leaf having a pintle and a locking-disk removably secured to said leaf, and having a slot therein, of a mating leaf having an elongated socket adapted to receive the pintle and a locking-lug to enter the slot, substantially as set forth.

2. The combination, with a hinge-leaf having a pintle and a locking-disk adjustably secured to said leaf and provided with a slot having an upwardly-inclined inner wall, of a mating leaf having an elongated socket adapted to receive the pintle and a locking-lug to enter the slot, substantially as set forth.

3. The combination, with a hinge-leaf having a pintle, a conical base to the pintle, and a locking-disk, of a mating leaf having an elongated socket and a locking-lug, substantially as set forth.

4. The combination, with a hinge-leaf having an integral bracket-plate and a locking device attached to the bracket-plate, and a

circular locking-disk having an integral pintle, inclined planes, the separated shoulders of which produce an open slot between them, and provided with spaced notches that are made to engage a locking-toe, of a mating hinge-leaf bearing an elongated socket-box, the walls of the socket being parallel to allow sliding motion on the pintle, substantially as set forth.

5. The combination, with a hinge-leaf having a laterally-projecting bracket-plate that is provided with a transversely-elongated boss which is vertically perforated with two parallel holes, of a locking-disk bearing an upwardly-projected pintle and a depending pintle that axially aligns with the upper pintle, and is adapted to engage either of the perforations in the bracket-boss, substantially as set forth.

6. The combination, with a hinge-leaf having a laterally-extended bracket-plate which is provided with a transversely-elongated boss that is perforated at two points equally distant from the center of the boss, transversely considered, of a locking-disk which is provided with an upwardly-projected pintle and a depending pintle located in the same vertical plane, a device attached to the locking-disk and hinge-leaf to lock the disk at any desired point, rotatively considered, a mating hinge-leaf having a vertical socket which has parallel walls and is elongated laterally to engage slidingly with the main pintle of the other leaf, and a depending locking-toe secured to said leaf, substantially as set forth.

In testimony whereof I affix my signature in presence of two witnesses.

WILLIAM P. PATTON.
